BURGLAR AND FIRE ALARM

Edgerton F. Taylor, New Haven, Conn., assignor
to Jack C. Lewis, New York, N. Y.

Application January 8, 1937, Serial No. 119,663

2 Claims. (Cl. 177—314)

This invention is a burglar or fire alarm of the type controlled or actuated by the interruption of a light ray, preferably an infra-red ray. An infra-red ray is preferable because it would

5 not be visible to the burglar. Such a ray would not only be interrupted by a burglar but would also be interrupted to a greater or less degree by smoke, and hence would serve as a fire alarm.

One of the important features of the invention 10 is that means is provided for taking a picture of the burglar in the act of committing the burglary which would prove valuable in identifying him in case of his capture later.

Another important feature of the invention is 15 that it is entirely independent of the usual commercial lighting circuit. This is of considerable importance, because the alarm is still operative and the photograph will be taken, even if the burglar should have the foresight to disconnect 20 or break the commercial circuit before entering the building.

In this local circuit, therefore, there is provided a camera, shutter actuating means for the camera and a flash bulb, all of which would be 25 operated to take a picture of the burglar upon interruption of the light ray.

Also in this local circuit there is an alarm 30 device. This could be a bell or siren; the same circuit could be used for actuating a radio set for sending out a radio signal either to the police 35 cars or to the police station, or both, or to send a signal over wires to the police station.

The described local circuit is provided with its own battery, which provides current for the 40 light ray and for the local circuit for actuating the camera, the light bulb and the radio or other signals just described.

While, therefore, the apparatus is operable independently of the commercial circuit and will 45 operate even if the commercial circuit is broken, nevertheless, in one aspect of the invention, a commercial lighting circuit is utilized, preferably for turning on one or more flood lights; the lighting of the flood lights would evidently make 50 the burglar discontinue his efforts at robbery, and would aid his capture. Another circuit is, therefore, provided, actuated upon the interruption of the light ray, for turning on the flood lights. There could also be provided in the same 55 circuit with the flood lights an alarm device such as a bell or siren and, if desired, a radio set for sending out a signal to the police cars or to the police station.

The camera shutter actuating means prefer- 55 ably comprises a small motor which operates

cam means which, in the order named, opens the camera shutter, closes the circuit through the flash bulb for setting it off, and then closes the camera shutter.

With the apparatus so far described, means 5 may also be provided for enabling a policeman or other authorized person to turn on the flood-light. To this end, a photoelectric cell is provided just inside the store window mounted in a suitable housing. A key-controlled door is 10 provided for protecting the photocell so that an unauthorized person cannot actuate it. In this aspect of the invention the preferred arrangement is that the cell actuate the floodlight only but, if desired, it could be arranged not only to 15 actuate the floodlight, but also to set the entire alarm apparatus in operation.

In the accompanying drawings illustrating the invention in more detail:

Fig. 1 is a diagrammatic view, partly in perspective, showing the wiring and mechanism of the improved burglar and fire alarm of this invention;

Fig. 2 is a diagrammatic view showing an arrangement for actuating the floodlight; 25

Fig. 3 is a sectional view of the housing for the photo-cell used in Fig. 2; and

Fig. 4 is a front view of the housing of Fig. 3.

Referring now to the drawings, the alarm system comprises a casing 2 containing a local battery 4, 6 which is connected by a lead 8 to an electromagnet or solenoid 10, through armature 12 and lead 14 back to the battery. A light ray producing source is indicated at 16, and is connected by leads 17 to the battery, producing 30 35 preferably an infra-red or other ray 18 which actuates the photoelectric cell 20. This cell is in circuit with a sensitive electromagnet 22 and actuates the armature 12. When the light ray is interrupted, magnet 22 causes armature 12 to 40 close the circuit, thereby causing the magnet 10 to attract its armature 24 which supplies current through lead 26 to the wire 28. This sends a current to the mechanism for taking 45 a picture, which will now be described.

30 diagrammatically illustrates a motor which drives a worm 32 which meshes with the interrupted worm wheel 34 and drives the shaft 36. Shaft 36 is provided with a cam having risers 38 and 40 which are adapted to engage with a 50 lever 42 pivoted at 43. The other end of the lever 42 engages a rod or lever 44 for actuating the shutter of a camera 46.

Also positioned on shaft 36 is a cam 48 arranged to contact a circuit closing lever 50 piv- 55

oted at 52. The lever 50 is in circuit with the battery 54 and a flash bulb 56. In place of battery 54, battery 4, 6 could be used. When the motor operates, shaft 36 is rotated and riser 38 5 engages lever 42 and opens the shutter of the camera. As the shaft continues rotating, cam 43 actuates lever 50 and closes a circuit through the flash bulb and sets it off, thereby exposing the film or plate in the camera. As the motor 10 continues to rotate, riser 40 of the cam engages lever 42 to close the shutter of the camera. After these operations have been completed, the interrupted portion of the worm wheel 34 reaches the worm 32 and although the motor may 15 continue to rotate, the worm wheel 34 will not be rotated any further. The mechanism just described will therefore take a picture of the burglar.

Wire 28 is also connected to an alarm 38 such 20 as a bell or siren. Wire 28 may also send a signal through wires 60 directly to the police station.

The apparatus can also be arranged to send a radio signal, either directly to the police station or to radio cars. To this end, a relay 62 is provided to be actuated by current from the wire 28, the closing of the relay actuating armature 64 to close the circuit from the local battery 66 through a time delay relay 68 and local stop switch 70 through a motor 72, wire 74 completing 30 the return circuit from the motor. The motor operates a train of gears indicated generally at 76, the gears operating a signal transmitting device 78 which may conveniently be a waxed cylinder of the phonograph type having a stylus 35 80 and sound reproducing head 82 connected to the radio sending set 84. The sending set is connected to wires 86 through the time delay relay 68, the return to the battery being shown at 88.

When, therefore, wire 26 is energized, the camera and flash bulb will be operated to take a picture, bell 58 will be rung and a suitable signal sent out from the radio sending set. The return wires from the several instrumentalities just mentioned are connected through wires 90 and 45 92 back to the local battery 4, 6.

From the foregoing, it will be apparent that the several signals just described are entirely independent of the commercial circuit.

The operation of a flood light from a commercial circuit will now be described.

Wire 26 is connected by wires 92 and 94 in shunt with the circuit closed by the armature 24 and when this latter circuit is closed, the electromagnet 96 is energized and armature 98 55 closes the circuit through contacts 99 and wires 101 and 102 to a flood light 103. A local knife switch 104 is provided, connected by leads 105 to the usual 110 volt lighting circuit 106.

Therefore, when the light ray is interrupted, 60 not only will the bell, camera and radio set be actuated, but the flood light 103 will also be lighted. The flood light may be of sufficient power for enabling the camera to take a picture by the light supplied thereby. However, even if 65 the commercial circuit is broken, the bell, camera and radio set will be actuated because they are not dependent upon the 110 volt commercial line for their operation.

Figs. 2, 3 and 4 show an arrangement whereby 70 the floodlight 103 can be lighted by the actuation

of a photoelectric cell. The photoelectric cell is preferably placed inside a store window, in a suitable casing, and is protected by a suitable cover, key-controlled, so that an authorized person, such as a policeman, can open the cover, 5 actuate the photoelectric cell by means of a flashlight and cause the floodlight 103 to be lighted and the interior of the store to be illuminated.

Referring now to Figs. 2, 3 and 4, a photoelectric cell 108 is in circuit with a magnet 109 and local battery 111 and controls a switch-closing armature 112 which is arranged, when the magnet is energized, to close a circuit through the floodlight 103 by means of the leads 113, 114 15 and 115 connected to the line 106.

The photoelectric cell 108 is mounted in a suitable casing 116 on the inside of a plate glass window 117. On the outside of the window there is secured a housing 118 having a door 119 having a key-controlled lock 120. An authorized person upon opening the door 119 could, by the use of a flashlight, actuate the photoelectric cell 108 to cause the circuit to be closed through the floodlight 103. This would not actuate the alarm. 20 As soon as the door 119 is closed, the floodlight is switched off by the armature 112. If it is desired to have the photo-cell 108 actuate the entire alarm system, the photo-cell would be connected in a shunt circuit, to energize magnet 10, 30 instead of magnet 109, which would light the floodlight and actuate the entire alarm, in the same way as if energized by interruption of the light ray 18.

While the present preferred embodiments of 35 the invention have been described in some detail, it should be understood that the invention is not to be limited to such details, but may be carried out in other ways, as falling within the scope of the claims.

I claim as my invention:

1. A burglar and fire alarm, comprising in combination a local circuit, a switch for closing said local circuit, means, including a photo-electric cell and cooperating light ray interruptable by a burglar or by smoke, for actuating said switch for closing said local circuit, a camera, means controlled by said local circuit for operating the camera upon the closing of said local circuit, battery means for said local circuit, a flood light, switch means for connecting said flood light to a commercial power line, and means in said local circuit for closing the switch for the flood light when the camera is operated.

2. A burglar and fire alarm, comprising in combination a local circuit, a switch for closing said local circuit, means, including a photo-electric cell and cooperating light ray interruptable by a burglar or by smoke, for actuating said switch for closing said local circuit, a camera, 50 means controlled by said local circuit for operating the camera upon the closing of said local circuit, an alarm device in said local circuit operable upon the closing thereof, battery means for said local circuit, a flood light, switch means for connecting said flood light to a commercial power line, and means in said local circuit for closing the switch for the flood light when the camera 55 is operated.

EDGERTON F. TAYLOR. 70
